UNITED STATES PATENT OFFICE.

EDWIN M. CORYELL, OF NEW YORK, N. Y., ASSIGNOR TO JULIA E. CAMERON,
OF SAME PLACE.

DESIGN FOR A FRAME FOR WATER ENDS FOR STEAM-PUMPS.

SPECIFICATION forming part of Design No. 32,133, dated January 23, 1900.

Application filed December 13, 1899. Serial No. 740,131. Term of patent 14 years.

To all whom it may concern:

Be it known that I, EDWIN M. CORYELL, a citizen of the United States, and a resident of the city and State of New York, have invented and produced a new and useful Design for a Frame for Water Ends for Steam-Pumps, which is fully set forth in the following specification.

Figure 1 is a perspective, and Fig. 2 is a plan.

A A represent the two water-chambers, shaped as shown. They lie end to end and are joined by the suction-pipe B and the union-pipe D, as shown, which are bolted to the chambers A at the flanges indicated, and the chambers A carry bolted thereto by the flanges the valve-chambers C C. The configuration of my design is symmetrical with respect to a transverse vertical plane and also with respect to a longitudinal vertical plane, except for the inlet and the projecting sides of the valve-chambers. More particularly, each water-chamber is of substantially the same length and height—*i. e.*, square—as viewed from the side, but of less thickness from side to side. It may have the central and the lower longitudinal swellings a, with the intermediate valley a', and it is rounded on the edges, except where it carries the four flanges hereinafter referred to.

B is the suction-pipe, resting on the base-flanges b, provided with the transverse elbow

that leads to the inlet B', and united to the water-chambers by flanges b', which are bolted to the corresponding flanges on the water-chambers. 35

C C are the valve-chambers, substantially cubes, but rounded at the edges, as shown, and each united to its water-chamber by the flange c, which is bolted to the corresponding 40 flange on the water-chamber. The bonnets C' are bolted to the projecting sides of the valve-chambers, while to their ends are bolted the plate C".

D is the union-pipe, substantially a flat- 45 tened U, connected to the water-chambers by flanges d, bolted to the corresponding flanges on the water-chambers, and at D' leading to the air-chamber and discharge. (Not shown.)

E are the glands, bolted by their flanges to 50 corresponding flanges on the water-chambers. At F is indicated the piston-rod.

Having described my invention, what I claim as new, and desire to secure by Letters Patent of the United States, is— 55

The design for a frame for water ends of steam-pumps, as herein shown and described.

In testimony whereof I have signed this specification in the presence of two subscribing witnesses.

EDWIN M. CORYELL.
